Application May 10, 1949, Serial No. 2,542

Term of patent 3½ years

(Cl. D34—4)

To all whom it may concern:

Be it known that we, Rudolph A. Wendelin and Ethel O. Kamm, citizens of the United States, residing in Arlington, in the county of Arlington and State of Virginia, and Washington, in the District of Columbia, respectively, have invented a new, original, and ornamental Design for a Doll, of which the following is a specification, reference being had to the accompanying drawing, forming a part thereof.

Fig. 1 is a face view of a doll, showing our new design; and

Fig. 2 is a side view of the doll; and

Fig. 3 is a rear view of the doll; and

Fig. 4 is a perspective view of the doll.

We claim:

The ornamental design for a doll, as shown.
RUDOLPH A. WENDELIN.
